UNITED STATES PATENT OFFICE

ANDREW C. DUNN, OF ST. PAUL, MINNESOTA

EARPIECE

Application filed March 13, 1923, Serial No. 624,768. Renewed September 16, 1929.

My invention relates to improvements in earpieces for the receiving mechanism of sound transmitting apparatus and in the method of producing such improved ear-
5 pieces.

Its object is to provide a simple, inexpensive, and durable earpiece of the present nature designed to be comfortably and securely held in the ear when worn by the user.

10 Another object is to supply a slightly earpiece of this kind adapted to be placed within the confines of the ear and securely, but detachably held therein by interlocking engagement with the ear folds.

15 A further object is to provide a device serving the dual purpose of a terminal mounting for sound receiving means and as an adapter for applying said receiving means to the external ear.

20 An additional object is to supply an earpiece having the advantageous characteristics above noted and providing for the enhanced bodily conduction of audible impulses.

A further object resides in the provision of
25 a novel method of producing earpieces.

With the foregoing and other objects in view, which will appear in the following description, the invention resides in the novel combination and arrangement of parts and
30 in the details of construction hereinafter described and claimed.

In the drawings, Figs. 1 and 2 are inner and outer elevational views of an earpiece embodying my invention; Fig. 3 is a side elevational view, a portion thereof being broken away to show interior construction and Fig. 4 is a view partly in elevation and partly in section, the same illustrating a pattern employed in my improved process of earpiece
35 production.

Referring to the drawings, it will be observed that the present earpiece consists of a body 10 having fin-like protuberances thereon. This body supplies a mounting for the
40 terminal of a sound transmitting apparatus, which, as shown comprises a sound conveying tube a . Said body 10 is shaped to fit the concha or central and largest concavity of the external ear. It envelops the tip a' of the tube a and a portion of the right turn a''

in said tube. Fitted within the ear, the body 10 holds the tube a in position with the tip a' thereof in registration with the auditory canal and the portion a'' of said tube on the other side of the right turn in depending relation for convenient attachment with associated parts. Protuberances 11, 12 and 13, on the body 10, fit in concavities of the ear and are respectively engaged by the cartilaginous folds or prominences known as the tragus, antitragus and antihelix. Thus it will be understood that the earpiece may be readily applied and removed and that when the same is in place within the ear, it is firmly interlocked therewith and capable of carrying the tube a without danger of accidental dislodgment.

The body 10 is made from suitable form retaining material, preferably capable of being cast in a mold.

I prefer to especially construct the earpieces for the individuals for whose use they are intended. It is obvious, however, that from a varied stock of standardized earpieces it is possible to obtain a comparatively close fitting earpiece for the average person. Preferably, in constructing an earpiece for a given ear, a core is centered therein and a self-hardening plastic substance kneaded about the same and into the central concavities to take an impression of the outer ear. The hardened, shaped substance, as at 18, together with the core 14 forms a pattern, which is used in accordance with common practice to make an ordinary mold (not shown), the ultimate body 10 being then cast of suitable material in said mold.

The core 14, as shown, is shaped like the curved tube a , a reduced tip 15 being formed thereon. Said tube occupies the seat in a mold formed by said core, a plug 16 (dotted lines, Fig. 3) capable of being removed from the end of the tube and adapted to form the inner opening 17 in the body 10 being inserted in said tube prior to the casting operation. A substance that has become set after being shaped in plastic condition within the ear may comprise the earpiece. So also may a cast material to which shape is given in a mold formed with a pattern produced in a

manner otherwise than that hereinbefore described.

Among other advantages resident in my improved earpiece, it will be readily appreciated that the limited visible part thereof is sightly; that said earpiece is comfortable to the wearer and secure against accidental dislodgment from his ear; that special or standard earpieces may be conveniently constructed and that said earpieces due to their intimate contact over relatively great areas with the roots of the ears enhance the bodily conduction of sound.

Changes in the specific form of my invention, as herein disclosed, may be made within the scope of what is claimed without departing from the spirit of my invention.

Having described my invention, what I claim as new and desire to protect by Letters Patent is:

1. An earpiece for a sound conveying tube having a right angular bend therein providing a normally horizontal branch and a normally depending branch, said earpiece comprising a body shaped to fit within the outer ear and formed about the bend in said tube, said body having an opening at its inner side bringing the horizontal branch of the tube into communication with the auditory canal of the ear and formed with protuberances thereon arranged to interlock with the ear folds at either side of said tube.

2. An earpiece for a sound conveying tube including a normally horizontal branch and a depending branch, said earpiece comprising a body of form retaining material shaped to fit within the outer ear and adapted to hold the horizontal branch of the tube with the open end thereof in registration with the auditory canal, said body having protuberances thereon to interlock with the ear folds.

In testimony whereof, I have signed my name to this specification.

ANDREW C. DUNN.
